COMMUNICATION SYSTEM

Harry Nyquist, Millburn, N. J., assignor to Bell Telephone Laboratories, Incorporated, New York, N. Y., a corporation of New York

Application June 6, 1941, Serial No. 396,839

11 Claims. (Cl. 179—18)

This invention relates to communication systems and particularly to a signaling means for use therein.

An object of the invention is to increase the speed of dialing.

Another object is to provide a signaling system in which the distance of the subscriber's station has comparatively little impairment upon the character of the pulses received by the central office switching mechanism.

Still another object is to eliminate pulsing contacts at the subscriber's station and to provide at the central office a pulse generator that actuates the switching mechanism with pulses more uniform in speed, percentage break, and current strength.

A further object is to provide a calling device in which a single impulse is transmitted for each digit dialed, the length of the impulse being proportional to the digit dialed.

Still a further object is to eliminate the customary mechanical governor and spring in a calling device and electrically return the dial to its normal position in synchronism with the operation of a pulse generator at a central office.

With the above objects in view, an embodiment of this invention discloses a system in which a simplified dialing unit having an inductor motor return movement is provided at the subscriber's station and in which a pulse generator operative in synchronism with said return movement is provided at the central office. The subscriber's dialing signal comprises a single impulse, rather than the commonly used variable impulses of equal length, for each actuation of the dial. The duration of this impulse varies in accordance with the digit dialed, and is of shortest period for the digit 1 and of longest period for the digit 0. The duration of dial return, therefore, determines the quantity of pulses generated by the pulse generator, which pulses in turn actuate the switching mechanism in the well-known manner. Since the pulses are generated in the central office rather than at the subscriber's station, they can be made more nearly uniform in speed, percentage break, and current strength and moreover, they can be made substantially uniform in shape.

A more complete understanding of this invention will be obtained from the detailed description which follows and by reference to the appended drawing which shows one embodiment thereof.

Referring to the drawing there is shown diagrammatically at one end of a transmission line 55

a telephone subscriber's station having a novel inductor motor type of calling device 10 and at the other end of the line, a central office having a pulse generator PG with associated control apparatus interposed between a line-finder circuit LF or a line switch (not shown), as the case may be, and a selector switch (not shown).

The calling device will be first described. In appearance the calling device is somewhat similar to the well-known impulse transmitting devices that are in common use in automatic telephone systems but is distinguished in that the governor, impulse cam, and transmitting springs have been omitted therefrom. In lieu thereof there is provided a special impulse transmitting unit which opens the line circuit once for each actuation of the calling device dial, the duration of the open circuit depending upon the digit in accordance with which the dial is operated.

20 The calling device 10 comprises a finger-hole dial 11 with the customary finger stop FS. Rigidly secured to the dial 11 by any suitable means is one end of a tubular member 12 which has mounted thereon at its other end a contact spring 13, which upon rotation of dial 11 also rotates therewith. Spring 13 is equipped at its free end with a contact 14 while intermediate therewith is fastened one end of a spring 15, the other end of which is insulated by an insulator 9 and secured in a suitable manner to a contact spring 16 having a contact 17 cooperating with contact 14. Contacts 14 and 17 are normally separated from each other by spring 15 but during the clockwise rotation of dial 11, 25 the pressure exerted by contact spring 13 upon separative spring 15 is sufficient to effect closure of contacts 14 and 17. Upon the return movement of the dial, as explained hereinafter, spring 15 is sufficiently strong to again separate contacts 14 and 17 inasmuch as the dial offers very little, if any, frictional resistance thereto.

Contact spring 16 is fastened to a shaft 18 which is insulatedly journaled at one end in tubular member 12 and at the other end in a frame (not shown) of the dial unit. Shaft 18 freely rotates in said journals and intermediate therewith is secured a hub 19 of an inductor 20 by any suitable means such as a pin 21. Hub 19 may be integral to inductor 20 or may comprise a separate element secured thereto. Around a large portion of the periphery of inductor 20 are arranged teeth 22, which, after having been rotated mechanically in a clockwise direction by the finger dial, are attracted by a stator 23 energized by alternating current through a winding

24 to cause the inductor 20 to rotate counter-clockwise and return to its normal position. A capacitance 25 of suitable value is inserted in series with winding 24 to prevent flow of direct current and permit flow of alternating current therethrough during the return movement of the dial 11. A cam 26 is also located on the periphery of inductor 20 between the end teeth 22 for actuating a switch 27 when inductor 20 is rotated from its normal position. The remaining apparatus at the subscriber's station comprise the usual transmitter, receiver, etc., that are well known in the telephone art.

The pulse generator PG at the central office will be described next. The line-finder circuit LF and the switching mechanism (not shown) will not be described as they are not vitally concerned with applicant's arrangement although at the same time they comprise elements well known in the switching art.

The pulse generator PG comprises a rotor 28 having teeth T of soft iron. Eight teeth are shown on said rotor but applicant does not limit himself to this number of teeth as the same speed of rotation may be obtained by other quantities of teeth. Rotor 28 is rigidly secured to a shaft 29 and rotates at a speed of 15 revolutions per second when energized from a 60-cycle source. That is, the rotor 28 advances two teeth in accordance with the attraction of first one electromagnet and then the other, as explained hereinafter, and since the rotor comprises eight teeth, it will make one revolution every four cycles. To one of the teeth T is affixed a pin 30 composed of soft iron or of permanent magnetic material in order to function as a south pole. The pin 30 is positioned in a plane different from that of the rotor teeth T.

Cooperating with the rotor 28 are electromagnets 31 and 32 having windings 33 and 34, respectively, thereon. Both windings are connected in parallel, winding 33 also being serially connected with an inductance 35 and winding 34 serially connected with a capacitance 36. Because of the inductance 35 and capacitance 36, the electromagnets 31 and 32 alternately energize at a phase displacement of 90 degrees, first one electromagnet being energized and then the other. This alternate energization of the electromagnets attracts rotor 28 in such manner as to cause its rotation in either direction at a speed dependent upon the frequency applied to the electromagnet. One embodiment which is disclosed herein, employs a sinusoidal frequency of 60 cycles.

After the pulsing operation has ceased, it is desirable to return the rotor 28 to its normal position. Applicant accomplishes this by locating a permanent magnet 37 in the same plane as that of pin 30, with the north pole N of magnet 37 opposite the south pole of pin 30. Upon de-energization of electromagnets 31 and 32, rotor 28 is released and pin 30 being attached thereto is attracted by magnet 37 to return the rotor 28 to its normal position. For this purpose magnet 37 is sufficiently strong to determine the rest position of the rotor 28, but at the same time weak enough not to interfere appreciably with the rotor's rotation.

A cam 38 is also rigidly secured to shaft 29, which likewise makes one revolution every four cycles. Cam 38 cooperates with an armature 39 and insulated arm 40 of a switch S to open normally closed contact 41 thereof. The contour of the cam 38 is so shaped as to break the switch

contact 41 sixty per cent of the time during each revolution of the cam; and thus provides optimum percentage break. In other words, during each revolution of the rotor 28, a break of 60 per cent duration occurs in the switching mechanism circuit. A restraining spring 42 effects intimate contact of armature 39 over the periphery of cam 38.

The control relays associated with the pulse generator at the central office are the ordinary telephone type relays of well-known construction. The functions of these relays will be explained fully during the description of the circuit operation. In addition to the control relays, condensers C1 and C2 and inductances L1 and L2 may be interposed in the talking path to separate the signaling from the voice channel. Resistance R may be inserted in the switching mechanism circuit to give the signal current generated by the pulse generator PG optimum value, while condenser C in parallel with resistance R may be added to reduce the transmission loss caused by resistance R if inductances L1 and L2 are small.

The operation of the dialing system will now be described. Upon removal of the receiver 43 from the switchhook 44, in order to initiate a call at a subscriber's station, a circuit is closed through the usual line relay (not shown) located at the central office. Closure of the line relay initiates the operation of a line finder in a manner that is well known. When the line-finder circuit LF is operated, a circuit is closed from the negative pole of battery 45, at the central office, through the upper winding of relay 46, conductor 47, line-finder circuit LF, and thence over conductor 48 of the transmission line through coil 49, over conductors 50 and 51, through transmitter 52, conductor 53, lower break contact of switch 27, conductor 54, lower make contact of switchhook 44, and back to the central office over conductor 55, through line-finder circuit LF, conductor 56, and thence through lower winding of relay 46 to positive pole of battery 45. Relay 46 energizes and immediately thereafter relay 57 operates in a circuit (not shown) to close its front contact and prepares a circuit for supplying alternating current both to the subscriber's line and to the pulse generator. The front contact of relay 57 is interposed in this circuit primarily to eliminate the continuous and wasteful operation of the pulse generator PG during idle periods and may be made a part of the well-known cut-off relay of the line circuit (not shown), which relay operates after the line finder has seized the calling line. Applicant, however, does not limit himself to the use of such relay as other means known to one versed in the art are available. Relay 46 in operating closes at its bottom front contact the pulsing circuit to the switching mechanism (not shown) and prevents at its upper contacts the application of alternating current to the calling device and pulse generator.

Meanwhile the usual tone signal is transmitted to the subscriber informing him that the central office switching mechanism is ready to receive his dial impulses. The calling subscriber now inserts his finger into one of the finger holes 58 and moves dial 11 clockwise until the finger stop FS has been reached. At the beginning of rotation of dial 11, contacts 14 and 17 engage after overcoming the resistance of spring 15 and shunt the lower break contact of switch 27 over conductors 59 and 60, which are connected directly to springs

13 and 16, respectively. Applicant, however, does not limit himself to this connecting means as other well-known means such as the slip ring and brush construction may be substituted therefor. In addition, the pressure of contact 14 upon contact 17 forces shaft 18, and in turn rotor 20, to rotate clockwise (in the direction of the arrow) with the dial. As rotor 20 moves clockwise, cam 26 disengages itself from switch 27 and opens the lower contact thereof. However, this has no effect as the closure of contacts 14 and 17 had already created a parallel operating circuit for relay 46. When the finger stop FS is reached, and the finger is withdrawn, contacts 14 and 17 are separated by the force of spring 15 thereby deenergizing relay 46. At the same time dial 11 starts back in a manner to be hereinafter described.

The release of relay 46 causes 60-cycle energy to be applied to the subscriber's line to inductively return dial 11 to its normal position. This circuit may be traced from the upper terminal of the 60-cycle source 61 through upper winding of relay 62, capacitance 63, conductor 64, lowermost upper back contact of relay 46, conductor 47, thence through line-finder circuit LF, over conductor 48, through coil 49, conductor 50, upper front contact of switchhook 44, conductor 65, upper front contact of switch 27, conductors 66, 53, and 68, through winding 24, capacitance 25, conductors 69 and 54, through lower make contact of switchhook 44, and back over conductor 55 through line-finder circuit LF, conductors 56 and 70, back contact of relay 46, conductor 71, capacitance 72, through lower winding of relay 62, conductor 73, and thence through front contact of relay 51 to bottom terminal of source 61. Relay 62 energizes over the above-traced circuit and closes the front contact thereof to maintain the pulsing circuit (as traced hereinafter) in a closed condition. The release of the bottom front contact of relay 46 is therefore retarded to permit prior energization of relay 62.

Stator magnet 23 is alternately energized and deenergized by the sinusoidal current from source 61 and attracts teeth 22 in a manner well known in the art to cause the rotor 20, and in turn, dial 11, to rotate counter-clockwise back to its normal position. The teeth 22 of rotor 20 may be of soft iron or may be so constructed that alternate ones are north and south poles. Furthermore, the teeth are so spaced that the speed of return is held accurately to a speed corresponding to fifteen pulses per second. After a time interval corresponding in length to the digit dialed, cam 26 closes the lower contact of switch 27, which energizes relay 46 in a circuit already traced. The operation of relay 46 disconnects 60-cycle source 61 and thereby releases relay 62. The interval during which 60-cycle energy is applied to the subscriber's line is one-fifteenth of a second if the digit 1 is dialed, two-fifteenths of a second if the digit 2 is dialed, and progressively to ten-fifteenths of a second when the digit 0 is dialed.

While the 60-cycle energy is applied to the line, it also is applied simultaneously to the pulse generator PG to cause the latter to likewise operate synchronously with the return movement of the calling dial 11. The circuit for energizing the pulse generator PG may be traced from the upper terminal of the 60-cycle source 61, over conductor 74, through uppermost back contact of relay 46, and thence in parallel paths, one path through winding 33 of electromagnet 31 and in-

ductance 35, and the other path through winding 34 of electromagnet 32 and capacitance 36, thence through upper back contact of relay 46, conductor 73, and through front contact of relay 57 to bottom terminal of source 61. As previously described, the electromagnets 31 and 32 are alternately energized and as a result cause the rotor 28 and cam 38 to rotate synchronously with the return movement of the dial 11 at a rate of fifteen revolutions per second. This synchronous rotation of rotor 28 of the pulse generator PG in turn opens the switching mechanism circuit at contact 41 once for each revolution, in a manner already described. This circuit may be traced from inductance L1 through back contact 41 of switch S, resistance R, over conductor 75, front contact of relay 62, over conductor 76, through inductance L2, and thence through loop of selector switch (not shown) back through inductance L1. Upon rotation of cam 38, the armature 39 with its insulated arm 40 is raised and lowered in such manner as to cause the back contact 41 of switch S to alternately break and make the above-traced circuit, which in turn steps the magnets (not shown) of the switching mechanism in the well-known manner. After the dial 11 returns to its normal position, relay 46 operates, as previously described, and disconnects the 60-cycle source 61 from windings 32 and 33 whereupon the pulse generator returns to its normal position in a manner already described.

When the subscriber dials the second digit, the above operations are repeated. This procedure continues until the proper number of digits have been dialed and the desired selection has been effected.

The connection is released in the usual manner by restoring receiver 43 to its switchhook 44 whereupon the subscriber's line circuit is opened to release line finder LF and relays 46 and 57. Relay 46 in releasing opens the switching mechanism circuit at the lower front contact thereof while relay 57 at its front contact disconnects source 61. The circuit is now in readiness for another call.

While the features of this invention have been disclosed with reference to a specific embodiment only, it is, of course, understood that various modifications may be made in the details of construction without departing from the scope of this invention as defined in the appended claims.

What is claimed is:

1. A signalling system comprising a reciprocating dial movable in accordance with different digital values and alternating current responsive means for restoring said dial to its normal position.
2. In a signalling system, a reciprocating dial movable in accordance with different digital values and inductor motor means for returning said dial to its normal position.
3. In a signalling system, a reciprocating dial movable in accordance with different digital values, an inductor motor for restoring said dial to its normal position, a source of alternating current for driving said motor, and impulse means driven by said source synchronously with said motor.
4. In a signalling system, a subscriber's substation, a reciprocating dial in said substation movable in accordance with different digital values, an electroresponsive device for returning said dial to its normal position, a source of alternating current at a telephone central office for driving said device, a line circuit extending be-

tween said substation and said central office, and impulse means at said central office driven by said source concurrently with said device.

5. A signaling system comprising a dial movable from its normal position in accordance with different digital values, an alternating current motor for returning said dial to its normal position, a source of alternating current for driving the motor, and a pulse generator driven by said source synchronously with said motor for producing impulses proportional in duration to the digit dialed.

6. In a signaling system, a calling device having a reciprocating dial, electroresponsive means for regulating the return movement of the dial at a predetermined speed after each setting thereof, a line circuit, a source of alternating current for actuating said electroresponsive means, and an electroresponsive device driven by said source synchronously with said means.

7. In a signaling system, a calling device having a reciprocating dial, a motor, a rotor and stator in said motor, a coupling connecting the dial with the rotor, a switch on said coupling, said switch being closed during the forward movement and opened during the return movement of said dial, and a winding on said stator in series with a condenser connected in parallel relationship with said switch, said condenser providing a closed circuit to alternating current and an open circuit to direct current during the return movement of the dial.

8. In a signaling system, a subscriber's station, a calling device at said station having a reciprocal dial, means in said device for transmitting a single impulse at each actuation of the dial, the duration of said impulse being proportional to the digit dialed, an impulse generator at a telephone central office, and means including a line circuit extending between said calling device and said generator for driving said impulse generator an interval of time proportional to the duration of said impulse.

9. In a signaling system, a calling device having a reciprocating dial, normally closed springs

and normally opened springs connected in parallel relationship, a capacitance and inductance connected in parallel with said springs, a source of direct current and of alternating current, means for maintaining said normally closed springs in an open condition and said normally open springs in a closed condition during the actuation of said dial to a finger stop thereof, thereby providing a closed circuit for direct current, means for opening said normally open springs during the return movement of said dial whereby said circuit is opened to direct current, and means responsive to said open circuit for connecting said alternating current source to said capacitance and inductance during the return movement of said dial.

10. In a signaling system, a calling device having a reciprocating dial, an electroresponsive pulse generator, a line circuit extending between said calling device and generator, means included in said calling device for opening the line circuit for a duration of time proportional to the digit dialed, means controlled over said line circuit responsive to the opening thereof for operating said pulse generator for the duration of said open circuit, and means for restoring said pulse generator to its normal position upon closure of said line circuit.

11. In a signaling system, a calling device having a reciprocating dial, an electroresponsive pulse generator, a line circuit extending between the calling device and generator, a source of direct current and alternating current, switch means included in said calling device for opening the line circuit to direct current and closing it to alternating current for a period of time proportional to the digit dialed, means controlled over said line circuit responsive to the opening thereof for operating said pulse generator for the duration of said open circuit, switch means periodically opened and closed during the operation of said pulse generator, and means for restoring said pulse generator to its normal position upon closure of said line circuit.

HARRY NYQUIST.
